ASPHALT LAYDOWN MACHINE

George W. Swisher, Jr., Oklahoma City, Don W. Smith,
Edmond, and Gary L. Westphall, Oklahoma City,
Okla., assignors to CMI Corporation

Filed Nov. 25, 1974, Ser. No. 526,536

Term of patent 14 years

Int. Cl. D15—04

U.S. Cl. D40—5

FIG. 3

FIG. 1 is a front, isometric view of an asphalt laydown machine showing our new design.

FIG. 2 is a side elevational view thereof.

FIG. 3 is a rear elevational view thereof.

We claim:

The ornamental design for an asphalt laydown machine, substantially as shown.
